CLAIM

The ornamental design for a flashlight, as shown and described herein.

DESCRIPTION

FIG. 1 is a top perspective view of a quick release mechanism of a flashlight of the present design;

FIG. 2 is a bottom perspective view of the quick release mechanism of the flashlight of FIG. 1;

FIG. 3 is a side elevation view of the quick release mechanism of the flashlight of FIG. 1;

FIG. 4 is a side elevation view from a second angle of the quick release mechanism in FIG. 1;

FIG. 5 is a top plan view of the quick release mechanism of the flashlight of FIG. 1; and,

FIG. 6 is a bottom plan view of the quick release mechanism of the flashlight of FIG. 1.

The broken line showing is for illustrative purposes only and forms no part of the claimed design.
